DESIGN FOR A HAIR DRIER

George Berrell Leather, Esher, England

Application January 18, 1949, Serial No. 310
In Great Britain September 23, 1948

Term of patent 14 years

(CL. D86—10)

To all whom it may concern:

Be it known that I, George Berrell Leather, a subject of the King of England, and resident of 77 Grove Way, Esher, Surrey, England, have invented a new, original, and ornamental Design for a Hair Drier, of which the following is a specification, reference being had to the accompanying drawings, forming part thereof.

I claim:

The ornamental design for a hair drier, as shown.

GEORGE BERRELL LEATHER.
